UNITED STATES PATENT OFFICE.

BENNO VOM EIGEN, OF NEWARK, NEW JERSEY, ASSIGNOR TO AUG. GOERTZ & CO., A CORPORATION OF NEW JERSEY.

DESIGN FOR A POCKET-BANK.

No. 39,217.

Specification for Design.

Patented March 24, 1908.

Application filed March 14, 1907. Serial No. 362,427. Term of patent 7 years.

To all whom it may concern:

Be it known that I, BENNO VOM EIGEN, a citizen of the United States, residing at Newark, in the county of Essex and State of New Jersey, have invented a new, original, and ornamental Design for a Pocket-Bank, of which the following is a specification, reference being had to the accompanying drawing, forming a part thereof.

In the said drawing, Figure 1 is a face view; Fig. 2 an edge view; and Figs. 3 and 4 are the respective end views of the pocket bank, shown in the design.

I claim:

The ornamental design for a pocket bank, as shown.

BENNO VOM EIGEN.
